PERCY B. CAMP, OF MAYWOOD, AND JACK WILSON, OF CHICAGO, ILLINOIS, ASSIGNEES
TO UNIVERSAL DRAFT GEAR ATTACHMENT CO., A CORPORATION OF ILLINOIS.

BRAKE MECHANISM FOR RAILWAY CARS.

Application filed December 6, 1924. Serial No. 754,287.

This invention relates to brake mechanisms for railway cars and has for its principal object to maintain the slack in the foundation brake gear and the hand brake at a constant value; to adjust the hand brake to compensate for an increase in slack in the foundation brake gear, and to make the movement incident to applying the brakes by means of the brake cylinder, shorten the hand brake as the slack in the foundation brake gear increases.

Further objects and advantages of the invention will become apparent as the disclosure proceeds and the description is read in connection with the accompanying drawing illustrating a selected embodiment of the invention, and in which—

Fig. 1 is a side elevation of a car under-frame, illustrating a brake mechanism embodying the present invention, parts being broken away;

Fig. 2 is a plan view of the same;

Figs. 3 and 4 are plan and side elevation of a six-wheel truck equipped with clasp brakes;

Fig. 5 is a plan view of an automatic slack adjuster for the hand brake and one form of multiplying lever that will first multiply the speed of the brake staff to quickly take up the slack and then multiply the power of the brake staff to apply the brakes;

Fig. 6 is a side elevation of the same;

Fig. 7 is an end view of the automatic slack adjuster;

Fig. 8 is a longitudinal sectional view of the automatic slack adjuster;

Fig. 9 is a plan view of an alternative form;

Fig. 10 is a partial longitudinal sectional view of the form shown in Fig. 9;

Fig. 11 is a partial transverse section taken on line 11—11 of Fig. 10, and

Fig. 12 is a perspective view of the pawl used in the modified construction.

The invention is particularly advantageous in connection with brake mechanisms of the kind disclosed in the patent to William H. Clegg, No. 1,558,840, issued Oct. 27, 1925, and for convenience is illustrated in connection therewith.

Referring to Sheet 1, (Figs. 1, 2, 3 and 4) 10 indicates a conventional brake cylinder that operates the cylinder levers 11 and 12,

cooperating through the cylinder lever connection 13, to transmit power of the cylinder 55 to the cylinder lever and floating lever connections 14 from which it is communicated to the floating lever 15 and, in turn, through the rods 16, to the brake levers 17, which cooperate with brake levers 18 through the 60 rods 19 and 20 to press the brake shoes 21 against the wheels 22. The cylinder lever 11 is fulcrumed at 23 on the piston 25 of the cylinder, and the cylinder lever 12 is fulcrumed to a movable cross-head at 24 65 which is adjustably connected to the pressure head of the cylinder 10.

The hand brake includes a brake staff 26 adapted to wind up a chain 27 and operate a multiplying lever 28 carried in a jaw 29 70 suitably supported on guides 30 and connected with the hand brake lever 31 by the hand brake rod 32. The hand brake lever is carried by a hand brake lever fulcrum 33, mounted beneath the car and is attached 75 to the foundation brake gear in this instance by fastening it to the cylinder lever and floating lever connection 14. This connection has a sliding joint 34 which permits the hand brake at one end of the car to apply 80 the brakes to one truck without applying them to the other truck.

In all types of brake mechanism wear on the brake shoe increases the slack in the foundation brake gear and in order to make 85 the travel of the piston in the cylinder 10 substantially constant it is necessary to compensate for this increase of slack. This is done by what is known as a slack adjuster 35 (Fig. 2) which moves the fulcrum of the 90 cylinder lever 12 to the left as the slack increases. The operation of this device is well known and a description may be found on page 841 of the Car Builder's Encyclopedia, 1922, published by Simmons-Boardman Publishing Co.

Heretofore, however, there has been no corresponding means to make the throw of the hand brake constant which becomes especially important with the devices for 100 quickly taking up a given amount of slack and then changing the mechanical advantage to apply the brakes with pressure comparable to that of the air brakes. For example, in Figs. 5 and 6, the multiplying lever has 105 a sector shaped arm 36 which receives the

power of the brake staff from the chain 27 and cooperates with the shorter arm 37 anchored to the car by chain 38 to move the jaw 29 with speed or power, as the case may be. This is fully set forth in the patent to Clegg, above referred to, and it will suffice here to say that with the parts in the position shown in Fig. 6, a slight movement of the chain 27 will revolve the lever through 10 90°, during which movement it multiplies the speed and takes up the slack, then upon further movement of the chain 27 the multiplying lever rotates slowly, and multiplies the power. If the slack in the brake mechanism exceeds the amount taken up by approximately a quarter of a turn of the multiplying lever, the efficiency of the device is reduced and the time necessary for applying the brakes is correspondingly increased. 15

According to the present invention the slack is maintained at a substantially constant value by shortening the hand brake and the motion incident to applying the brakes with air pressure is used to make the 20 compensating adjustment.

In the construction shown in Figs. 5, 6, 7 and 8, Sheet 2, the jaw 29 is equipped with a guide 39 of hexagonal cross section within which is a rack 40 of similar cross section 30 having teeth 41 on its upper faces for cooperation with a pawl 42, housed in a pocket 43 on top of the guide.

In all brake mechanisms the hand brake is operatively connected with the foundation 35 brake gear and some of its parts move each time the brakes are applied by the air pressure. In this instance each application of the brakes by the air pressure rocks the hand brake lever 31 and reciprocates the hand 40 brake rod 32. By connecting the rack 40 to this hand brake rod the rack is made to partake of that movement. When the travel of the piston does not exceed the normal the rack 40 will merely move to the right (Fig. 45 8) in the guide 39, and then back again to the position shown, the pawl 42 traveling with the rack without releasing it. However, should the wear on the brake shoes cause the piston travel to exceed the normal, the rack 50 would move further to the right and the pawl 42, coming in contact with the wall 44 of the pocket 43, would be checked. If the rack 40 continues to the right the width of one tooth 41, the pawl will ride upwardly 55 in the pocket 43 and drop into the next set of notches. Then, when the brakes are released and the parts assume their normal slack position, the hand brake will be shorter by the width of one tooth 41. Subsequent 60 brake applications will produce a reciprocation of the rack and pawl without changing their engagement until the slack increases sufficiently to let the rack move beyond the normal width of one tooth, when another 65 compensating adjustment will take place.

This will continue until the brake shoes are worn down to the point where replacement is necessary.

By inclining the upper wall 45 of the pocket 43 the pawl 42 is automatically locked 70 in engagement with the rack when any stress is to be transmitted and is permitted to release the rack by riding up the inclined faces of the teeth 41 when an adjustment is to be made. In order to restore the pawl to normal position at the right end of the rack when new brake shoes are put in, the rack is pushed to the right manually and the pawl is raised and the rack slid back to the left and the pawl lowered. The position of the 80 pawl is controlled manually by the U-shaped yoke pivoted at 46 having one arm 47 serving as a handle, while the other arm 48, extends through the pawl.

The right end of the guide is equipped 85 with a stop 49. For convenience in manufacture this stop may be cast integral with the guide. The upper and lower faces of the rack conform to the corresponding faces in the guide, but the lateral faces of the rack 90 are shorter than the corresponding faces on the guide which results in ample clearance between the teeth and the upper portion of the guide. This difference in size also makes possible the assembly of the guide and the 95 rack. The side of the guide next to the arm 36 of the multiplying lever is cut away along the line 50 (see Figs. 5 and 7). By tilting the rack to the left in Fig. 7 it may be inserted into the guide past the stop 49. 100 In the form shown in Fig. 8 the rack 40 is threaded to the rod 32, as shown at 51, and the guide and rack are provided with aligned openings 52 and 53 to permit the operator to see when the threaded engagement 105 is complete.

In the alternative form illustrated in Figs. 9, 10, 11 and 12, Sheet 3, the brake rod 32 extends through an aperture 54 in the end of a rack 55 which is provided with 110 a chamber 56, receiving a nut or collar 57 on the end of the brake rod and permitting it free relative movement of the length corresponding to the normal piston travel. The rack is mounted in a guide 58, similar to the 115 guide 39, and for convenience they are provided with aligned openings 59 and 60 through which the nut 57 may be inserted in assembling. The pawl 61 is pivoted at 62 in an enlargement of the guide and carries 120 at its free end a pivoted jaw 63, having teeth 64, for cooperation with the corresponding teeth 65 on the rack 55. The guide is provided with longitudinal flanges 66 connected by reinforcing ribs 67 to give it ample strength 125 to withstand the thrust on the pawl.

In this construction a normal piston travel merely causes the nut 57 on the brake rod 32 to move forward and back in the chamber 56. Any additional piston travel will re- 130

sult in the nut striking the rear wall 68 of the chamber 56 and the rack will begin to move to the right in Fig. 10. If this movement continues for the length of a tooth 65, 5 the pawl will drop into the next space between teeth and thus shorten the hand brake and compensate for that amount of slack in the foundation brake gear.

The invention, whether embodied in the 10 forms illustrated or otherwise, provides means for automatically taking up the hand brake to compensate for an increase of slack and therefore keeps the slack in the mechanism as a whole at substantially constant 15 value thereby maintaining the operation of applying brakes by hand at a uniform standard.

Use has been made of specific description 20 and illustration in order to disclose the invention, but it is intended that nothing contained herein shall unnecessarily limit the following claims, or require a construction thereof that would permit the substance of the invention to be used without infringement. 25

We claim as our invention:

1. In a brake mechanism, the combination of a foundation brake gear, a brake cylinder for operating the foundation brake gear, 30 and a hand brake for operating the foundation brake gear, including a hand power device and means connecting the hand power device and the foundation brake gear automatically operable to adjust the hand brake during the brake applying movement of the foundation brake gear by air to compensate for slack.

2. In a brake mechanism, the combination of a foundation brake gear, a brake cylinder 40 for operating the foundation brake gear, and a hand brake for operating the foundation brake gear, including relatively movable elements operated when the brakes are applied by air pressure to adjust the hand brake to compensate for slack in the foundation brake gear.

3. In a brake mechanism, the combination of a foundation brake gear, a brake cylinder for operating the foundation brake gear, and 50 a hand brake for operating the foundation brake gear, including an element moving with the foundation brake gear when the air pressure is applied and a second element cooperating with said moving element to shorten the hand brake to compensate for slack in the foundation brake gear when the movement of the first element under the action of the air pressure exceeds a predetermined amount.

4. In a brake mechanism, the combination of a foundation brake gear, a brake cylinder for operating the foundation brake gear, and a hand brake for operating the foundation brake gear, including two elements one 60 of which moves with the foundation brake

gear when the air pressure is applied, and means permitting free relative movement of said elements in one direction and limiting their relative movement in the reverse direction, whereby the hand brake is automatically adjusted upon the movement of one element with the foundation brake gear during the application of the brakes by air. 70

5. In a brake mechanism, the combination of a foundation brake gear, a brake cylinder for operating the foundation brake gear, and a hand brake for operating the foundation brake gear, including a rack and pawl mechanism operated by the application of the brakes with air pressure to shorten the 80 hand brake.

6. In a brake mechanism, the combination of a foundation brake gear, a brake cylinder for operating the foundation brake gear, and a hand brake for operating the 85 foundation brake gear including a rack moving when the air pressure is applied, a pawl cooperating with the rack upon excess movement of the rack by the air pressure to automatically adjust the hand brake to compensate for slack. 90

7. In a brake mechanism, the combination of a foundation brake gear, a brake cylinder for operating the foundation brake gear, and a hand brake for operating the foundation brake gear including two elements one of which moves with the foundation brake gear when the same is operated by the brake cylinder and means permitting free relative movement of said elements in both directions within a selected range of travel, but curtailing the reverse movement when that range is exceeded. 95

8. In a brake mechanism, the combination of a foundation brake gear, a brake cylinder, 105 a piston in the brake cylinder connected with the foundation brake gear, a hand brake for operating the foundation brake gear, including means operated by the movement of the piston during an air brake application to automatically adjust the hand brake to compensate for slack when the piston exceeds its 110 normal travel.

9. In a brake mechanism, the combination of a foundation brake gear, a brake cylinder, 115 a piston in the brake cylinder connected with the foundation brake gear, a hand brake for operating the foundation brake gear, including two relatively movable elements, one of which is constrained to travel 120 with said piston, and means to shorten the reverse movement of the last mentioned element relative to the other element when the piston exceeds its normal travel.

10. In a brake mechanism, a foundation 125 brake gear, a brake cylinder for operating the foundation brake gear, a hand brake for operating the foundation brake gear, including means to take up the slack quickly and then apply the braking pressure, and means 130

to shorten the hand brake to compensate for an increase of slack in the foundation brake gear.

11. In a brake mechanism, a foundation brake gear, a brake cylinder for operating the foundation brake gear, a hand brake for operating the foundation brake gear, including means to take up the slack quickly

and then apply the braking pressure, and means for maintaining the slack in the hand 10 brake and foundation brake gear substantially constant.

In testimony whereof we affix our signatures.

PERCY B. CAMP.
JACK WILSON.
